The ornamental design for combined camera and mount system for a vehicle, as shown and described.

DESCRIPTION

FIG. 1 is a frontal perspective view of a combined camera and mount system for a vehicle illustrating my new design, with top and bottom camera units pivotally attached to the hanging bracket for mounting the system to a vehicle windshield;

FIG. 2 is a reduced left elevational view thereof;

FIG. 3 is a reduced front elevational view thereof with a rear view mirror shown in phantom lines to illustrate environment for the system;

FIG. 4 is a reduced right elevational view thereof, also showing the mirror of FIG. 3 in phantom lines;

FIG. 5 is a rear elevational view thereof;

FIG. 6 is a top plan view thereof; and,

FIG. 7 is a bottom plan view thereof.

The broken line showing of a rear view mirror is for illustrative purposes only and forms no part of the claimed design.
